UNITED STATES PATENT OFFICE.

CHARLES H. HOWARD, OF AUBURN, MAINE, ASSIGNOR TO JEFFERSON S. BAILEY, OF MILFORD, MASSACHUSETTS.

SLASHER.

SPECIFICATION forming part of Letters Patent No. 350,054, dated September 28, 1886.

Application filed December 19, 1885. Serial No. 186,174. (No model.)

To all whom it may concern:

Be it known that I, CHARLES H. HOWARD, of Auburn, county of Androscoggin, and State of Maine, have invented an Improvement in 5 Slashers, of which the following description, in connection with the accompanying drawings, is a specification, like letters on the drawings representing like parts.

This invention has for its object to lay in 10 one direction the fibers of the yarn being sized or acted upon in a slasher or in any usual warp-sizing machine.

In slashers as now made brushes are employed to act upon and lay the fiber uniformly 15 in one direction; but the employment of brushes is considered objectionable, because the brushes are kept wet or damp, owing to the application of water thereon in the process of keeping the brushes clean. Pieces of board 20 placed above and below the sheet of warp being sized have been covered with cloth, the cloth coming in contact with both the upper and lower sides of the sheet of yarn; but such wipers are considered objectionable because, 25 upon the stoppage of the machine for any reason, the warp-threads are liable to become stuck fast upon the cloth, and so also the cloth becomes coated with size, and the yarn is sometimes broken between the boards covered 30 with cloth, and the broken end is at that point clogged or caught. In accordance with my 35 invention the yarn, as it passes from the sizing-vat to the usual drying-drum, is led between wiping-surfaces, preferably made as 40 rolls covered with cloth, the said rolls being placed alternately above and below the sheet 45 of warp, the latter being drawn between and in contact with the said wiping-surfaces, which effect the laying of the fibers in one and the same direction, the said rolls being by suitable 50 links or connecting devices placed in operative connection with the belt-shipper, so that upon the stoppage of the machine for any cause the wiping-surfaces are removed from contact with the sheet of warp.

My invention consists, essentially, in the combination, with wiping-surfaces and a belt-shipper, of intermediate connecting mechanism, whereby the wiping-surfaces are removed 55 from contact with the sheet of warps when the

machine is stopped through the action of the belt-shipper.

Figure 1 is a partial side elevation of a sufficient portion of a warp-sizing machine to enable my invention to be understood. Fig. 2 55 is a top or plan view of Fig. 1, the sheet of warp being, however, omitted. Fig. 3 is an enlarged sectional detail showing part of one of the stands, the rock-shaft, and one of its carrying-arms, parts of the wiping-surfaces, 60 and the gearing for rotating the same. Fig. 4 is a section of Fig. 3 in the line $x-x$; and Fig. 5 shows a modified form of wiping-surfaces, to be referred to.

The frame-work A, the drying-drums A' A'', 65 the main shaft a , the belt-pulleys $a' a''$ thereon, the belt-shipper fork b , the rock-shaft b' carrying it, the link b' , the shipper-lever b'' , the size-box B, the rolls therein between which the sheet of warp is passed, and the guide- 70 rolls $c' c''$ are all substantially as in the class of slashers now commonly in use and fully illustrated in No. 98, Vol. 9, of the journal, called "The Textile Manufacturer," dated February 15, 1883, published by Emmott & Co., 75 of Manchester, England, among advertisements. On the frame-work I have erected bearings d , on which I have placed the rock-shaft d' , to which is attached inside the said frame, near each side thereof, arms e , the opposite ends of which are provided with bearings to receive the journals $e' e''$ (see Fig. 4) of the 80 wiping-surfaces $f' f''$, the said wiping-surfaces being shown as rolls, which, in practice, will be covered with cloth or other fibrous material of proper nature to act upon the warp w and lay the loose fiber thereof in one direction. At one end thereof the rock-shaft d' is extended through a bearing-sleeve, f , which is supported in one of the uprights d , the said 85 sleeve having at one end a belt-pulley, f^3 , and at its opposite end a pinion, f^4 . The journals $e' e''$ of the wiping-surfaces $f' f''$ are provided, respectively, with pinions $g' g''$. The pinion f^4 engages and rotates the pinion g^2 , and 90 with it the wiping-surface f^2 . The pinion f^4 , at its opposite side, engages the intermediate h on the stud h' in one of the arms e , and the said intermediate h engages a pinion, g' , on and 95 rotates the wiping-surface f' . The upper roll, f^1 ,

i, of the size-box B has upon one end of it a pulley, 2, (see Fig. 2,) which has extended about it a belt, 3, that is extended about the pulley *f*³. The roll *i* is rotated by friction 5 against the roll *i'* below it, the said rotation being effected substantially as in the machine hereinbefore referred to. The speed of rotation of the pulley *f*³, and the surface speed of the wiping-surfaces *f'* *f*², being preferably about 10 one-fourth as fast as the speed of the warp through the slasher, or the speed being sufficient to serve to lay the fibers of the yarn all in one direction without any disturbance or matting. I prefer that the wiping-surfaces 15 should be rotated slowly, as described, and in a direction opposite that of the movement of the warp or other threads being sized; but instead thereof, if desired, I may employ stationary bars, also marked *f'* *f*² and shown in 20 Fig. 5, the said bars, covered with textile material, as stated, being fixed to the arms *e* on the rock-shaft *d'*.

In accordance with my invention the end 25 of the rock-shaft *d'* opposite that where is located the pulley *f*³ is provided with an arm, *m*, which by the link or connecting-rod *m'*, is joined to the shipper-handle *b'*. When the shipper-handle *b'* is in the position shown in 30 Fig. 1, the wiping-surfaces *f'* *f*² stand in the full-line position represented in Fig. 1, and the wiping-surface *f'* bears against the upper side of the sheet of warp, while the upper side of the wiping-surface *f*² acts against the under side of the sheet of warp *w*, so that the warp, 35 as it is carried through the machine, is, by the said wiping-surfaces, so rubbed or subjected to friction and rubbing in such direction to lay all the projecting fibers of the individual warp-threads in one direction. So long as the 40 machine is kept in operation the wiping-surfaces referred to keep the position stated; but as soon as the belt-shipper is moved to carry the belt from the fast pulley to the loose pulley *a'*, the movement of the shipper-lever *b'* 45 through the link *m'* turns the rock-shaft *d'*, so that the wiping-surfaces *f'* *f*² keep the position shown by dotted line, Fig. 1, in which position both of the wiping-surfaces are removed 50 from contact with the warp-threads, so that as the machine stands at rest the warp-threads

and wiping-surfaces do not become stuck together.

From the above it will be obvious that the position of the wiping-surfaces with relation to the sheet of warp is absolutely under the 55 control of the belt-shipper, and so long as the belt-shipper is in position to keep the belt on the fast pulley just so long will the wiping-surfaces remain in contact with the upper and under surfaces of the sheet of warp; but as 60 soon as the belt-shipper is moved to shift the belt upon the loose pulley, thus stopping the rotation of the usual warp-receiving beam, not herein shown, but common to the machine referred to, then the wiping-surfaces are automatically and simultaneously removed from 65 contact with the warp.

I do not desire to limit my invention to the exact construction of the connecting devices between the shipper-lever and the rock-shaft 70 2, and instead of the particular devices or parts herein shown for such purpose I may employ any other usual or well-known equivalent devices.

I claim—

1. The wiping-surfaces and the shaft to support them and the shipper-lever, combined with intermediate connecting mechanism, substantially as described, whereby the position of the wiping-surfaces with relation to the sheet 80 of warp is controlled automatically by the movement of the belt-shipper in one or the other direction, substantially as described.

2. The wiping-surfaces, means, substantially as described, to rotate the said wiping-surfaces and the shaft to support them and the shipper-lever, combined with intermediate connecting mechanism, substantially as described, whereby the position of the wiping-surfaces with relation to the sheet of warp is 85 controlled automatically by the movement of the shipper-lever in one or the other direction, substantially as described.

In testimony whereof I have signed my name to this specification in the presence of two 95 subscribing witnesses.

CHARLES H. HOWARD.
